PERFORATING AND SLOTTING PUNCH

Karl J. Braun, Glenbrook, Conn., assignor to
Remington Rand Inc., New York, N. Y., a corporation of Delaware

Application July 17, 1948, Serial No. 39,275

18 Claims. (Cl. 164—112)

1

The present invention relates to a perforating and slotting device, and more particularly to a device adapted to perforate simultaneously a plurality of index positions adjacent an edge of a record card and further adapted to notch out the card material between certain of said perforations and said card edge.

Briefly, an indexing system is presently in use wherein record cards are peripherally perforated, which perforations are arranged in numbered groups, and data is codified and entered in said cards by notching out certain of said perforations. This system has come to be known as "sequence sorting" and is described in Patent 2,342,517 to D. A. Nevin. As seen therein, data is efficiently and simply entered in record cards which, through the use of various types of needling selectors, are readily adapted to be sorted according to common data therein.

A number of devices are on the market for codifying data and entering same in a record card by notching out card perforations. However, certain of such devices require the use of cards which have been peripherally perforated in their manufacture, thus limiting the indexing systems employing said devices to the use of "standard" or "pre-punched" cards.

Also, cards of particular sizes are necessarily used in some others of said devices. Still others are adaptable to operate on cards of varied sizes only when special adjusting means are employed.

Therefore, it is the principal object of the present invention to provide a device which obviates the prerequisite use of "standard" or "pre-punched" cards and is, therefore, operable on any file of record cards, to render them employable in the above mentioned sorting system or the like.

Another object of the present invention is to provide a device for operating on record card edges of varied lengths without mechanical adjustments being made to said device. In addition to adapting the device to operations on the contiguous edges of cards of a particular size, this provision readily adapts the device to like operations on cards of varied sizes.

Another object of the present invention is to provide means for plurally perforating a record card adjacent an edge, and for subsequently notching out the material between certain of said perforations and the card edge in accordance with a code. In this manner data is easily entered in a record card, and in such form it is readily sortable.

2

Another object of the present invention is to provide a device adapted to gang punch a card first, and to subsequently notch a card in accordance with a full keyboard set-up of the data to be entered in said card. Thus, due to the fact that an operator more readily senses "set-up" errors and can eliminate same in the present device before they are entered in a card, operational errors and card wastage are lessened.

10 Also, the adaptation of gang punching therein is a desirable time saving feature.

Another object of the present invention is the provision of a means for locking a "set-up" in the keyboard, in order to effect a repetitious operation in accordance with a previous "set-up." It will be obvious that such a provision is desirous when identical data is to be entered in a number of cards.

Another object of the present invention is 20 the provision of disabling means for selectively rendering ineffective any portion or portions of the perforating and notching means. This provision assures no operation in the card columns or fields other than those being intentionally utilized and, thereby, lessens the possibility of operational error.

Still another object of the present invention is to provide a device capable of concomitantly operating on a plurality of cards, a decided time saving provision when numerous cards are being handled, and data to be entered is identical for certain of said cards.

Other objects and structural details of the invention will be apparent from the following 35 description when read in connection with the accompanying drawings, wherein:

Fig. 1 is a general plan view of the machine which illustrates the relative locations of the various mechanisms and a preferred arrangement of the keys, and includes a fragmentary view of the keyboard for indicating the disposition of the various elements thereof;

Fig. 2 is a right hand side view of the machine illustrating the arrangement of the several 45 controlling and operating mechanisms;

Fig. 3 is a transverse sectional view of the machine taken along the line 3—3 in Fig. 1, looking in the direction of the arrows for illustrating the arrangement of certain of the punch 50 effecting mechanisms;

Fig. 4 is an isometric view of a group of code slides for illustrating the manner in which they are positionable by certain of their related keys to cooperate with corresponding bell-crank;

55 Fig. 5 is an isometric view of the double revolu-

tion clutch controlling mechanism for demonstrating the manner in which the trip mechanism holds the clutch engaged and the motor circuit unbroken for two rotations of the drive shaft;

Fig. 5A is an isometric view of the second bail lever;

Fig. 6 is a fragmentary sectional view taken along the line 6-6 in Fig. 2 for indicating the relative positions of the various stub and transverse shafts;

Fig. 7 is a fragmentary isometric view of the shifting mechanism and illustrates the mechanical and operational relationship existing between the bail and the card stop plate;

Fig. 8 is a diagrammatic chart indicating the approximate time relationship between the various mechanisms during the operational period devoted to each card;

Fig. 9 is a fragmentary face view of an index card of the type employable in the present machine, illustrating card edges which have received machine operations; and

Fig. 10 is a fragmentary face view of a prepared index card of the type usually employed in the present machine, and also illustrates card edges which have received machine operations.

As seen in the drawing, and particularly in Figs. 1, 2, and 3, the device is provided with a base plate 10, to which are rigidly secured left and right keyboard frames 11 and 12, respectively, and left and right side members 13 and 14, respectively. A keyboard assembly 15, which will be described in detail hereinafter, is suitably mounted between said frames 11 and 12 and is at an angle of inclination favorable to the operation thereof, and a die section 16 is secured at either of its ends to the side members 13 and 14. Now with particular reference to Figs. 2, 3, and 6, it is seen that a stub clutch shaft 17 and a stub cam shaft 18 are rotatably mounted in the right side member 14, and a punch mechanism shaft 19 and a shifting mechanism shaft 20, which are transverse, are similarly mounted in the side members 13 and 14.

The keyboard assembly 15, as best seen in Figs. 1 and 2, comprises twelve columns, each of which has eleven keys 21 with the indicia "one" through "nine" representing numeric values, an "R" for "Release," and an "L" for "Locking." A description of but one column will herein suffice, since the twelve mentioned columns are identical in construction.

As taught in the aforementioned patent, four index card positions may be evaluated as "7," "4," "2," and "1," and singularly or in combinations may be utilized for the recording of numeric data. Therefore, as shown in Figs. 1, 3, and 4, each keyboard column of the present machine is provided with a complement of four code slides 22, hereinafter referred to as #7, #4, #2, and #1, which slides are slidably mounted for to and fro movement between a forward comb plate 23 and a rearward comb plate 24 to cooperate with bell-crank 25. Resilient means, which will be described in detail hereinafter tend to hold all of said slides 22 in their most forward and ineffective position with respect to the bell-cranks 25. Each code slide 22 is configured to provide eleven cam lugs 27 on its upper side having cam surfaces 28 thereon and an abutting lug 29 on its lower side. The majority of the lugs 27 are further shaped to provide recesses 30 therein, whereas certain of said lugs are not. As will be best seen in Fig. 4, the #1 slide is formed with the recesses

30 in all of the cam lugs 27 with the exception of those related to the "Release," "1," "3," "5," and "8" keys; the #2 slide has said recesses 30 in all cam lugs 27 with the exception of those related to the "Release," "2," "3," "6," and "9" keys; the #4 slide has recesses 30 in all cam lugs 27 with the exception of those related to the "Release," "4," "5," and "6" keys, while the #7 slide has recesses 30 in all of its cam lugs 27 with the exception of those related to the "Release," "7," "8," and "9" keys.

All of the keys 21 are similar in construction and, as shown in Figs. 3 and 4, are provided with bent over portions 31, which portions are sufficiently wide to cooperate with the cam surfaces 28 of the four code slides 22 related thereto. A coil spring 32 is provided to maintain the keys 21 in a normally raised and ineffective position, and to urge them to the normal position following any operation thereof. It will be apparent that, due to the camming action between the portions 31 and the cam surfaces 28, the operation of any key 21 will initially motivate rearwardly all four code slides 22 related thereto. Further, it will be apparent that, should a portion 31 encounter cam lug recesses 30 in all four related slides, all of said slides will be returned to the normally ineffective position by the above mentioned and hereinafter to be described resilient means, and will thereby lock the key down. However, should said portion 31 encounter any cam lugs 27 not having recesses 30 therein, the slides 22 related thereto will be maintained in a rearward effective position against the tension of said resilient means, while those having recesses will be returned and will effect the locking down of the key.

In more detail, and with particular reference to Fig. 4, the operation of the "nine" key causes the #2 and the #7 code slides to be maintained in their rearward effective positions, the remaining slides being restored to normal and locking the "nine" key down. If the "two" key had been operated the #2 code slide would have been maintained in its forward position. It is believed unnecessary to describe further the numeric key operations, since it is apparent that the remaining ones of said keys merely render effective the code slides singularly or combinationally in a manner identical to that hereinabove described. When the above mentioned "Locking" key "L" is operated, the bent over portion 31 thereon will encounter four cam lug recesses 30 and will lock thereunder. A finger 33 on said "Locking" key extending below the plane of the code slides 22 is provided to cooperate with a slide retracting mechanism to disable said mechanism, and thereby permit repetitious operation on a particular keyboard set-up. Operation details concerning the "Locking" key will hereinafter follow in connection with the description of said slide retracting mechanism.

The "Release" key "R" is adapted upon operation to motivate rearwardly all four code slides in the column pertaining thereto, and will release all previously operated and consequently held down keys in said column, including the "Locking" key. Thus, a machine operator may operate the "Release" key to both wipe out an erroneous keyboard set-up and to eliminate locked-in data by rendering the "Locking" key ineffective.

A shaft 34, as seen in Figs. 3, 4, and 6, is suitably mounted at the rearward end of the aforesaid keyboard assembly 15, and carries loose

thereon the bell-cranks 25 which correspond in number to the code slides 22 and are accurately positioned with respect thereto by a comb member 35.

At the left end of the shaft 34, and also loosely mounted thereon, is an independent bell-crank 36 which, unlike the aforesaid bell-cranks 25, is not arranged to cooperate with a code slide or any other controlling means. Said bell-crank 36 is utilized in effecting the punching of a card "lifting" or "handling" hole in all cards, and is not used for data entering purposes. The manner in which said punching is effected is identical to the simultaneous perforating of the edge of all cards, which is to be explained hereinafter. Therefore, no further reference shall be herein made to the independent bell-crank 36 as such. Each of the bell-cranks 25 is provided with an appendant arm and a rearwardly extending arm, and in operation the rearward motivation of one of the aforementioned code slides, in consequence of a key operation, rocks the appendant arm of its corresponding set bell-crank 25 counter-clockwise, thereby raising the rearwardly extending arm to an effective position.

The die section 16 (Figs. 2 and 3), which extends the width of the device, is made in four pieces, and is suitably secured as an assembly to the left and right side members 13 and 14. Both the forward and rear die pieces 39 and 40, respectively, are slotted, said slots being aligned with the aforementioned bell-cranks 25. A forward upper bar 41 is affixed to the forward die piece 39, forming guide holes 42 to receive and guide therein punch elements 43.

Also attached to the forward upper bar 41, and partially obstructing the guide holes 42, is a retaining plate 44 for retaining the punch elements 43 in said guide holes 42 in a manner to be hereinafter described. A rear upper bar 45 is similarly secured to the rear die piece 40 and completes a die for the above mentioned punch elements 43. In this particular embodiment the forward die piece 39 and the rearward die piece 40 are preferably secured together at their ends by machine screws 46 (Figs. 1 and 2). The arrangement of the elements comprising the die section 16 is such that a card chamber 47 is provided for receiving the lower edges of the card or cards to be operated on. An abutment or side gage 26 fixed to the left hand extremes of the upper die pieces 41 and 45 (Figs. 1 and 3) limits transverse movement in one direction of said card or cards to insure the proper perforating and slotting operations thereon. It shall be clear that a suitable card engaging abutment may be provided on a machine cover for the present device, not herein shown instead of on the said die pieces 40 and 45.

Now, as is indicated in Fig. 3, the forward portions of the punch elements 43 are suitably formed to slide freely in the guide holes 42 and are each formed with a head 48 and a shoulder 49. As the drawing shows, a punching operation consists of advancing the punch elements 43 through a card and thereafter returning them. The heads 48 are adapted to be engaged by the punch actuator, as will be described, in order that a return movement may be imparted to the punch elements 43. The return movement is limited and the elements are retained in their guide holes 42 by the abutment of the shoulder 49 with the retaining plate 44.

As best seen in Fig. 6, the clutch stub shaft 17 is mounted in the right side member 14 and

is driven by an electric motor 50, to which it is connected by suitable speed reduction gearing 51. A transformer 52 is provided to adapt the present device for use with various voltages. 5 With reference to Fig. 2, it is seen that a toothed clutch disc 53 is fast on the stub shaft 17 which extends through the right side member 14. Loosely mounted on the stub shaft 17 and just inside of the disc 53 is a clutch plate 54 upon 10 which is pivotally mounted a pawl 55, having a nose 56, which pawl is cooperable with said disc 53. A spring 57, tensioned between the clutch plate 54 and the pawl 55, urges said pawl in a counter-clockwise direction into engagement 15 with the clutch disc 53. However, the pawl 55 is normally held in the disengaged position shown in Fig. 2 by a forwardly extending arm 58 of a three armed bail lever 59 formed as shown in Fig. 5, and pivotally mounted as at 60 to the side member 14. A second arm 61 of the bail lever 59 extends forwardly and is formed with a pair of steps 62 and 63 at its forward end, adapted to engage a toe 64 on an appendant arm 65 of a second bail lever, formed as shown in 20 Fig. 5A, which straddles the side member 14 and pivots on a pin 67. Formed on arm 65 is a bail 66 having an appendant arm 78. A spring 68, connecting the bail 66 and the arm 58, urges said bail 65—66—78 in a clockwise direction, and 25 in the normal stopped condition of the machine the toe 64 of the appendant arm 65 is positioned in the step 62 of the arm 61.

A bail shaped lever 69 having a hooked end 70 also straddles the side member 14, pivots on 30 the pin 67, and lies under the bail 66 to which it is resiliently connected by a spring 71. The lever 69 has secured to its bail portion a spring metal electrical contact 72 cooperable with a pair of contacts 73 mounted on side member 14 forming a part of the motor circuit. In normal position the contacts 72 and 73 are open.

If, however, the second bail lever is permitted to rock clockwise under the influence of the spring 68, the bail 66 thereon will act upon the lever 69 and the contacts 72 and 73 will close, thereby starting the motor 50 and rotating the clutch disc 53. The motor 50 will continue to run as long as the circuit remains unbroken. Bail lever 59 is formed with a third arm 74 (Fig. 2) which is upstanding and is connected to a forwardly extending link 75. The link 75 is moved forwardly when it is desired to start the machine, thereby rocking the arm 61 of bail lever 59 in a counter-clockwise direction. This movement permits the toe 64 of said appendant arm 65 to move under influence of spring 68 into the second step 63 of arm 61. As previously mentioned, the arm 58 of the above bail lever 59 normally holds the pawl 55 disengaged, and it will be seen that the counter-clockwise rocking of said bail lever 59, in addition to starting the motor 50 and the rotation of the clutch disc 53, will also permit the pawl 55 to engage the teeth of said clutch disc 53, thereby causing the clutch plate 54, upon which the pawl is mounted, to rotate with the disc. The direction of rotation of the clutch disc 53 and the clutch plate 54 is counter-clockwise, as viewed in Fig. 2, so that the plate will be disengaged from the disc upon the restoration of the arm 58 to normal position, since the forward end of the arm will re-engage the pawl nose 56. The clutch plate 54 is formed with a cam nose 76 on its outer periphery, this cam nose being adapted to cooperate with a bar 77 mounted between arm 78 and the appendant arm

65 of the second bail lever. In the normal position of the machine, as viewed in Fig. 2, the bar 77 is positioned just below and to the right of the cam nose 76 and, as the second bail lever 65—66—78 moves clockwise to start the machine, said bar moves forwardly to a spot just beneath the cam nose 76. Now, near the end of every cycle of the clutch plate 54, the nose 76 contacts the bar 77, and thereby rocks the second bail lever rearwardly in a counter-clockwise direction. Through spring 71 the lever 69 is urged to rock counter-clockwise also, which would break the motor circuit and return arm 58 to normal under tension of the spring 68. However, since the present embodiment of the invention is adapted to be operated on two complete cycles, the above mentioned tripping mechanism, which will be described hereinafter, provides means for maintaining the bail lever 59 in its counter-clockwise position after the first cycle. In this manner the arm 58 is prevented from returning to normal and a second cycle is immediately initiated. Also, as can be best seen in Fig. 5, the upwardly extending arm 74 of the bail lever 59 is formed with a nose 86 which, when said lever is in its counter-clockwise position, is adapted to cooperate with a roller 79 on the lever 69. With this arrangement the rearward movement of the second bail lever 65—66—78, caused by the action of the cam nose 76 and the bar 77, acts only to stretch the spring 71, and the motor circuit is not broken.

Affixed to the clutch plate 54 is a drive gear 80 for driving an idler gear 81 which in turn drives a gear 82 keyed to the aforementioned cam shaft 18. Said gear 82 is in a one to two ratio with the drive gear 80 and, therefore, the cam shaft 18 completes one revolution for every two revolutions of the clutch shaft 17.

At the right side of the keyboard assembly 15 (Figs. 1 and 2) is a trip key 83 having a downwardly extending arm 84, slidably connected to the right keyboard frame 12 by a pin and slot connection 85. The lowermost end of the arm 84 is pivotally connected to a forwardly extending arm of a bell-crank 87, the other arm of which is connected to the aforementioned link 75. Adjustably secured to the link 75 is an L-shaped member 88 which carries on its upright arm a roller 89 adapted to cooperate with a trip cam 90 keyed to the cam shaft 18.

With the above description in mind, and with particular reference to Figs. 2 and 5, it will be apparent that the operation of the trip key 83 will rock the bail lever 59 counter-clockwise to start the motor 50 and permit the pawl 55 to engage the clutch disc 53, thereby initiating a first machine cycle. Also, it will be seen that the roller 89, which normally rests on a low dwell of the trip cam 90 will ride upon the high portion and thereby hold the bail lever 59 in its counter-clockwise position. As was explained hereinabove, the cam shaft 18 to which the trip cam 90 is keyed rotates once for every two revolutions of the clutch shaft 17. Therefore, the bail lever 59 will be held in its counter-clockwise position until well after a second machine cycle has begun. Near the end of said second machine cycle the roller 89 will again ride on the low dwell 91, permitting the release of the pawl 55 and the breaking of the motor circuit to stop the machine (Fig. 8).

A punch actuating mechanism is provided for impelling the aforesaid punch elements 43 through a record card and withdrawing them

therefrom. This mechanism, as shown in Figs. 2 and 3, comprises left and right hand bell-crank 92 and 93, respectively, located outside of the side members 13 and 14 and fixedly secured to the ends of the punch mechanism shaft 19 mounted in said side members. A transverse channel 94 is secured at its ends to the upwardly extending arms 95 and 96 of said bell-crank 92 and 93. Secured between said arms is a transverse bar 97 to which is attached a comb plate 98 and a slotted plate 100. The slots in plates 98 and 100 correspond in number with the code slides 22, are vertically aligned with respect to each other, and are positioned to lie directly over the previously described bell-crank 25. Interponents 102, having rearwardly extending arms 103 and limiting shoulders 104, are slidably mounted in said comb 98 and slotted plate 100 and due to the length of the slots in said plate 100, a considerable amount of play exists between said interponents and said slots. As best seen in Fig. 3, weak springs 105 resiliently connect the rearwardly extending arms 103 with the comb plate 98 and thereby urge the interponents 102 to engage the bell-crank 25 and thus provide the resilient means whereby the said code slides 22 are urged to their normally ineffective positions. The limiting shoulders 104 are adapted to engage the comb 98 to thus determine the downward extent to which the springs 105 may urge the interponents 102. Suitably mounted at the under side of the transverse channel 94 is a U-shaped comb member 101 in which is positioned a shaft 106 carrying loose thereon setting levers 107 equal in number to the interponents 102, and disposed in said comb so as to be associated with said interponents. The setting levers 107 are provided with shoulders 110 and 111 to permit their being positioned in effective and ineffective relation with the interponents 102. Detent springs 112 are further provided to cooperate with the shoulders 110 and 111 for holding the setting levers in either their effective or ineffective settings. It will be seen that in operation said setting levers 107 may be manipulated to selectively render the interponents 102 effective or ineffective, thus controlling the operations of the corresponding punch elements 43. In an effective setting (Fig. 3) the rear of said setting levers 107 are engageable with raised interponents 102 upon the clockwise rocking of the bell-crank 92 and 93 and a rearward movement of the transverse channel 94. This engagement and movement effects the pushing of the related punch elements 43 through a card in the chamber 47. When any of said setting levers 107 are set to be ineffective, the rear ends thereof are raised and incapable of engagement with related raised interponents 102 during a rearward movement of the channel 94. If an interponent is unintentionally raised in a column in which the setting lever is in its ineffective position, the rearward movement of the channel 94 causes said interponent to engage the related punch elements 43. However, as a result of the aforementioned play existing between said interponents and the slot in the plate 100 and the weakness of the springs 105, further rearward movement of the channel 94 serves only to pivot said interponent counter-clockwise and to stretch the related spring 105 without pushing the related punch elements 43 through the card. In this manner a machine operator may manually select the columns in which it is desired that punching be permitted by disabling all others.

To an appendant arm of bell-crank 92 (Figs. 3 and 6) is pivotally connected a horizontal link 114, the forward end of which is connected by a pin 115 to a lever 116 loose on a transverse shaft 117 fitted in the side members 13 and 14. An adjustable dog 118 is fastened to the left end of the shaft 117 and is also connected by the pin 115 to the lever 116. At the right side of the machine and pivotally connected to an appendant arm of the bell-crank 93 (Fig. 2) is a second horizontal link 120, the forward end of which is connected by a pin 121 to a downwardly extending arm 122 of a bell-crank 123 loose on the shaft 117. Also, connected by the pin 121 to the arm 122, is a second dog 124 adjustably fastened on the right end of the shaft 117. The rearwardly extending arm of the bell-crank 123 is provided with an elongated slot 125 in which fits a stud 126 affixed to the hereinabove mentioned clutch plate 54. The just described arrangement, and more particularly the provision of the adjustable dogs 118 and 124, affords a convenient and efficient means for the adjustment of clearances in the punch actuating mechanism.

As previously explained, the clutch plate 54 completes two rotations before the declutching thereof and, in consequence of the stud 26 riding in the slot 125 and because of the above arrangement of elements, the shaft 19 will be twice oscillated. With reference to Fig. 3, it will be seen that an oscillation of the shaft 19 rocks bell-cranks 92 and 93 which carry the setting levers 107 and interponents 102. It will also be seen that if an interponent 102 were raised between a corresponding effectively set setting lever 107 and a punch element 43, the clockwise rotation of bell-cranks 92 and 93 would result in said element 43 being pushed past the cutting edge formed by the die piece 40 and the bar 45. The subsequent counter-clockwise rotation would then cause a wall 127 of the channel 94 to engage the shoulder 48 of the punch element 43 to withdraw said element.

Inside of the frame member 14 and keyed to the aforementioned stub shaft 18 is a shift cam 128 (Figs. 3, 6, and 7), upon the periphery of which rides a roller 129 carried on an arm 130 of an upper lever 131 fast on a shaft 132, and a roller 133 carried on an arm 134 of a lower lever 135 fast on a shaft 136. The forward ends of said levers 131 and 135 are pivotally connected as at 137 and 138 to a vertical link 139, having a stud 140. At the left hand side of the machine there is an arrangement of elements similar to that just described and includes an upper arm 141 fast on the shaft 132, a lower arm 142 fast on the shaft 136, and a vertical link 143 pivotally connected therebetween and having a stud 144. The aforementioned shifting mechanism shaft 20 has secured near its left end an arm 145 having a slot 146 therein for receiving the stud 144, and near its right end an arm 147 having a slot 148 therein for receiving the stud 140. Secured between the free ends of the arms 145 and 147 is a bail 149 which is adapted to cooperate with the aforementioned bell-cranks 25, in a manner to be hereinafter described. Also fast on the shaft 20, but extending rearwardly, are arms 150 and 151 having pivotally connected therebetween a bar 152 to which is affixed a card stop plate 153 provided with serrations 154 in its upper edge corresponding to the notches in said die pieces 39 and 40. As seen in Fig. 3, this card stop 153 is slidably mounted in a slot in the card chamber 47 and limits the extent to

which the edge of a card may be positioned in said chamber.

The operation of the shifting mechanism is such that in the starting position of the machine the arms 145 and 147 are as shown in Fig. 3, and, as a result, the bail 149 engages the rearwardly extending arms of all the bell-cranks 25 to raise and render effective the associated interponents 102. Also, the card stop plate 153 is 5 concomitantly in its lowermost position in the card chamber 47. These positions are maintained for half a cycle of the cam shaft 18, or as long as the lower roller 133 rides on the high dwell of the cam 128. Now, when the upper roller 129 10 rides on said high dwell during the second half of the cycle of cam 128, the arms 145 and 147 are caused to rock counter-clockwise lowering the bail 149 and raising the card stop plate 153 to its 15 uppermost position in said card chamber 47.

With particular reference to Fig. 2, it will be seen that a cam stud 155 is fixed in the wall of the gear 82, and is so located as to cooperate with an upper arm of a lever 157 pivoted as at 153 to the side member 14. Connected to the lower arm 20 of said lever 157 is a link 160, the forward end of which is loosely fitted on a retract bail 161. Triangular shaped levers 162 and 163 (Figs. 2, 3 and 6) are similarly fitted on the retract bail 161 just inside of the left and right side members 13 and 14, respectively, and are mounted on a transverse shaft 164. Just inside of the levers 162 and 163, and connected thereto by pins 165, are dog pieces 166 and 167, adjustably fast on the shaft 164. This arrangement permits both an even transmission of motion through the several elements, and adjustments thereto. Springs 168 are provided to urge said levers 162 and 163 to their most counterclockwise position. As best shown in Figs. 3 and 6, retract plates 169 are provided, one for each keyboard column to cooperate with the four code slides thereof. The forward portions of said plates 169 are formed to hold springs 170, the other ends of which are connected to hooked members 171, appropriately spaced on the shaft 164. This arrangement holds the abutting ends 172 of the retract plates 169 in the raised and operative position shown in Fig. 3. In operation, the aforementioned cam stud 155 cooperates with the upper arm of the lever 157 near the end of a cycle of the cam shaft 18, or near the end of a second machine cycle (Fig. 8). Thus, the lower arm is rocked in a counter-clockwise direction and, through link 160 and the bail 161, a slight rearward movement is imparted to all of the retract plates 169 against the tension of the springs 168 to engage the abutting lugs 29 of the code slides 22 and thereby releasing all the previously operated numeric keys. The "Locking" keys 173, however, 35 provide for rendering the described retract means ineffective. As readily seen in Fig. 4, each of said "Locking" keys 173 has formed thereon a finger 33 extending below the code slides 22 and adapted to cooperate with its associated retract plate 169. It will be seen that the operation of a "Locking" key 173 depresses its corresponding retract plate 169 to an ineffective position, in which it is unable to cooperate with the abutting lugs 29 of its related code slides 22.

The "Release" keys 175 (Figs. 3 and 4) are provided to release all previous key set-ups in their associated columns, including that of the "Locking" keys 173. The operation of one of said "Release" keys 175 acts to motivate rearwardly 40 its four related code slides 22, thus permitting

the spring 32 to elevate all of the previously operated keys 21 to an inoperative position.

Summary of operations

The machine operation as a whole will be described with respect to the use of but one keyboard column, since all such columns operate identically. As best shown in Fig. 4, the operation of a numeric key 21 acts to raise and hold in an effective position one or a combination of bell-crank 25. Following the keyboard set-up and the insertion of a card in the punching chamber 47, the "trip" key 83 is operated to complete the motor circuit and to permit the pawl 55 (Fig. 2) to engage the clutch disc 53 on the shaft 17 and cause the clutch plate 54 to rotate therewith. The cam shaft 18 is suitably geared to rotate at one half the speed of said clutch plate. Therefore, a cam thereon cooperates with the roller 89 on the trip link 75 to maintain the trip mechanism operative for two machine cycles (Fig. 8).

During the first machine cycle the card shifting mechanism, which holds the aforementioned card in its punching position, is in its lowered position, and the bail 149 holds all of the bell-crank 25 in their raised and effective positions (Fig. 3), thus positioning the interponents 192 between the setting levers 197 and the punch elements 43.

The stud 126 on the clutch plate 54 and the bell-crank 123 coact to oscillate the shaft 117 and impart a rocking movement to the punch actuating mechanism. It will be seen that through the channel 94, the setting levers 197 and the interponents 192, such rocking movement is sufficient for advancing the whole complement of punch elements 43 through the card to punch the handling hole 176 and the perforations 177 (Figs. 9 and 10) and to withdraw them therefrom.

Near the end of the first machine cycle (Fig. 8) the card shifting mechanism raises the card to a slotting position. Concurrently, the bail 149 is lowered and the only bell-crank 25 to remain effective during a subsequent slotting operation are those which were previously set up in the operation of the keyboard 15.

The slotting operation consists of shifting the card and slotting out the portion 178 (Figs. 9 and 10) of the card material between a perforation and the card edge. This is accomplished during the second machine cycle when the card is raised. Shortly after the slotting operation the stud 155 affixed to the wall of the gear 32 arrives at a point where it cooperates with the aforementioned arm of the lever 157, slightly rocking said lever in a counter-clockwise movement. Through link 160 and the retract bail 161, said rocking movement is transferred to the retract plate 169 which abuts the lugs 29 on its associated code slides 22 and retracts the numeric set keys 21 to their normal unset positions, thereby permitting said code slides 22 to return to normal also. If, however, the corresponding "Locking" key 173 is in its operated position, it will be seen that the retract plate 169 shall be ineffective. It will be further seen that the "Release" key 175 is operable to retract all previously set keys, including the "Locking" key 173.

Near the end of the second machine cycle the card shifting mechanism shifts the card stop plate 153 to its lower or perforating position, which might be considered the normal stopping and starting position. Also, shortly thereafter and just prior to the end of the second machine

5

cycle the flat dwell 91 on the trip holding cam 90 comes in contact with the roller 89 on the trip link 75, permitting the disengagement of the clutch and the breaking of the motor circuit to stop the machine.

From the above description of the present invention it is believed apparent that an efficient device has been provided for perforating a record card adjacent an edge and subsequently slotting out the material between selected ones of said perforations and the card edge. For instance, it will be obvious that the arrangement of the elements comprising said device may be such as to provide a selective slotting operation first, and a subsequent perforating operation, the reverse of the operations described herein.

While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention as hereinbefore set forth, and as herein-after claimed.

What I claim as new, and desire to secure by Letters Patent, is:

1. In a device of the class described, a single set of punches for perforating and for slotting file cards in separate stages, said punches being arranged for perforating a card adjacent an edge, means for displacing said card, and means for selectively rendering only certain of said punches effective, to thereby notch out the material between certain of said perforations and the card edge after the card has been displaced.

2. In a device of the class described, a single set of punches for perforating and for slotting file cards in separate stages, said punches being arranged for simultaneously perforating a card adjacent an edge, means for displacing said card, and key operated means for selectively rendering only certain of said punches effective simultaneously to thereby notch out the material between certain of said perforations and the card edge after the card has been displaced.

3. In a device of the class described for perforating and for slotting file cards in separate stages, the combination of a single set of punches adapted to be operated simultaneously for perforating a card adjacent one edge thereof, means for selectively rendering certain of said punches again effective simultaneously to notch out the card material between certain of said perforations and the card edge, and a card shifting means for effectively positioning said card with respect to said punches during the separate perforating and slotting stages.

4. In a machine of the class described for perforating and for slotting record cards in separate stages, a single set of punches effective simultaneously during a first machine cycle for perforating a card adjacent an edge, means for displacing said card, and key operated means for selectively rendering only certain of said punches effective simultaneously during a second machine cycle, to thereby notch out the material between certain of said perforations and the card edge after the card has been displaced.

5. In a machine of the class described for perforating and for slotting cards in separate stages and for sorting purposes, a single set of punches arranged in a plurality of groups and adapted to be effective simultaneously for perforating a

75

card adjacent an edge, means for displacing said card, and key operated means for selectively rendering only certain of said punches in any group effective simultaneously, to thereby notch out the card material between certain of said perforations and the card edge after the card has been displaced.

6. In a machine of the class described for perforating and for slotting record cards in separate stages, a single set of punch elements for perforating a card adjacent an edge when said card is in a perforating position, a card shifting means for moving said card from said perforating position to a slotting position, key operated means for rendering certain of said punch elements effective to slot out the card material between certain of said perforations and the card edge when said card is in said slotting position, and means for retracting said key-operated means.

7. In a machine of the class described for perforating and slotting record cards, a plurality of punch elements for perforating a card adjacent an edge when said card is in a perforating position during a first machine cycle, a card shifting means for moving said card from said perforating position to a slotting position during a second machine cycle, key-operated means for rendering certain of said punch elements effective to slot out the card material between certain of said perforations and the card edge during said second machine cycle, means for retracting said key-operated means at the end of said second machine cycle, and manual locking means for rendering said retracting means ineffective.

8. In a device of the class described, the combination of a plurality of punching elements, a common actuating means, a plurality of pre-settable members carried by said actuating means, each of said pre-settable members being related to a punching element and pre-settable to be effective or ineffective, and a plurality of interposing elements effectively positionable between said pre-settable members and punching elements for causing the operation of those punch elements related to effectively set pre-settable members.

9. In a perforating and slotting machine of the class described for operating on record cards, the combination of a plurality of punches, a common actuating mechanism, a plurality of interposers cooperating with said actuator when effectively positioned to operate all of said punches, a common means operative for effectively positioning said plurality of interposers and moving a card to one of two positions, said common means also being operative to shift said card to the other of said two positions and to be ineffective with respect to said interposers, and key-operated means for maintaining selected interposers in effective position.

10. In a perforating and slotting machine of the class described, the combination of a card shifting mechanism for automatically and cyclically moving a card vertically to one of two positions, a plurality of punches, a punch actuating means operable independently of said punches and in timed relation with said card shift mechanism, a plurality of interponents all positioned in effective relation with said actuating means and said punches for simultaneous operation when said shifting mechanism is in one position, and a key-operated means for selectively maintaining certain of said interponents in effective position when said shifting mechanism is in the other position.

11. In a perforating and slotting machine of the class described, the combination of a card shifting mechanism for automatically and cyclically moving a card vertically to one of two positions, a plurality of groups of punches, an actuating means common to all of said punches operable independently of said punches and in timed relation with said card shift mechanism, a plurality of groups of interponents all positioned in effective relation with said actuating means and said punches for simultaneous operation when said shifting mechanism is in one position, and key-operated means for selectively maintaining certain of said interponents in any group in effective position when said shifting mechanism is in the other position.

12. In a perforating and slotting machine of the class described, the combination of a plurality of punches, a cyclically operative punch actuating mechanism, a plurality of interposers positionable to render said punch actuating mechanism effective to operate said punches, a bail member for effectively positioning all of said interposers during a first machine cycle and for releasing said interposers during a second machine cycle, key-operated selecting means for retaining certain of said interposers in effective position during said second machine cycle, locking means for maintaining effective said selecting means, and manual means for releasing said selecting and locking means.

13. In a machine for perforating and slotting cards of index systems, the combination of a plurality of punches, a punch actuating mechanism operable independently of said punches, a plurality of interponents positionable to render said punch actuating mechanism effective to operate said punches, a card shifting mechanism for shifting a card vertically from a first position to a second position, a bail member constituting a part of said card shifting mechanism adapted to effectively position all of said interponents for simultaneous operation when said card is in said first position, and key-operated means for retaining certain of said interponents in effective position when said card is in said second position.

14. In a machine for perforating and slotting cards of index systems, the combination of a plurality of punches, a punch actuating mechanism adapted to be automatically operative every machine cycle, a plurality of interponents positionable to render said punch actuating mechanism effective to operate said punches, a vertically movable card support for positioning a card relative to said punches during a first machine cycle, a shifting mechanism for vertically displacing said card support automatically during a second machine cycle, a bail member connected to and coacting with said shifting mechanism for effectively positioning all of said interponents for simultaneous operation during said first machine cycle, and key-operated means for effectively positioning for simultaneous operation selected ones of said interponents during said second machine cycle.

15. In a machine for perforating and slotting cards of an index system, the combination of a die section, a plurality of punch elements positioned in said die section, a cyclically operative punch actuating mechanism, a plurality of interposing members positionable to render said punch actuating mechanism effective to operate said punches, a card stop for positioning a card relative to said punches during a first machine cycle, a shifting mechanism for displacing said card

stop during a second machine cycle, a bail member coacting with said shifting mechanism and effectively positioning all of said interposing members during a first machine cycle to effect the simultaneous perforation of said card adjacent an edge, key-operated means for effectively positioning selected ones of said interposing members to effect the notching out of the material between certain of said perforations and the card edge during a second machine cycle, and manually presettable means for selectively rendering said interposing members ineffective.

16. In a machine for perforating and slotting cards of an index system, the combination of a die section, a plurality of punch elements positioned in said die section, an independent punch element positioned in said die section, a cyclically operative punch actuating mechanism, a plurality of interposing members adapted to associate with said plurality of punch elements, an independent interposing member adapted to associate with said independent punch element, all of said interposing members being positionable to render said punch actuating mechanism effective to operate all of said punch elements, a card stop for positioning a card relative to said punch elements during a first machine cycle, a card shifting mechanism for displacing said card stop during a second machine cycle, a bail member coacting with said card shifting mechanism and effectively positioning all of said interposing members during a first machine cycle for simultaneously operating all of said punch elements to perforate said card adjacent an edge thereof and for operating said independent punch element to perforate a card handling hole, key-operated selecting means for effectively positioning one or more of said plurality of interponents to render associated punch elements effective to notch out the card material between certain of said perforations and the card edge during a second machine cycle, means for retracting said selecting means at the end of said second cycle, key-operated locking means for rendering said retracting means ineffective, manual means for releasing said selecting and locking means, and manually preset-

table levers for selectively rendering said plurality of interposing members ineffective.

17. In a device for perforating and for slotting out to an edge file cards in separate stages, a card shifting mechanism for vertically moving a file card automatically from one to another of two positions, a single set of punches supported in fixed coplanar relation, punch actuating means including selectively settable levers, some of said punches being effective in one plane to simultaneously perforate said file card with perforations when the card is in one position, and keyboard controlled means for selectively rendering certain of said selected punches in said same plane effective singularly or combinationally to slot out to an edge of the card certain of the perforations when the card is in the other position.

18. In a device for perforating and for slotting out to an edge file cards in separate stages, a card shifting mechanism for vertically moving a file card from one to another of two positions, a single set of punches supported in fixed coplanar relation arranged in a plurality of groups being effective in one plane to simultaneously perforate said file card with perforations when it is in one position, and means for selectively rendering one or more of said punches in any group in said same plane effective to slot out to an edge certain of the perforations when the card is in its other position.
